CLAIM

The ornamental design for a remote controlled vehicle, as shown and described.

DESCRIPTION

FIG. 1 is a perspective view of the front, right side and top plan of a remote controlled vehicle showing my new design, with a hoist in seated position;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a perspective view of the front, right side and top plan view thereof with the hoist in an upright position.

The broken lines represent portions of the design that form no part of the claim.

1 Claim, 5 Drawing Sheets

FIG. 1
